DESIGN FOR A COMBINED SPOON AND
CUP MEASURER

Lois E. Middleton, Oakland, Calif.

Application December 3, 1946, Serial No. 135,240

Term of patent 14 years

(Cl. D44—9)

To all whom it may concern:

Be it known that I, Lois E. Middleton, a citizen of the United States of America, residing at Oakland, in the county of Alameda, and State of California, have invented a new, original, and ornamental Design for a Combined Spoon and Cup Measurer, of which the following is a specification, reference being had to the accompanying drawing, forming a part thereof wherein;

Figure 1 is an elevational view of a combined spoon and cup measurer, showing my design.

Figure 2 is a vertical sectional view taken on the line 3—3 of Figure 3;

Figure 3 is a top plan view; and

Figure 4 is a bottom plan view thereof.

I claim:

The ornamental design for a combined spoon and cup measurer, as shown.

LOIS E. MIDDLETON.
